(57) **CLAIM**

Sep. 17, 2010 (JP) 2010-22529

The ornamental design for a screw for injection molding machine, as shown and described.

(51) **LOC (9) Cl.** **15-09**

DESCRIPTION

(52) **U.S. Cl.** **D15/135**

(58) **Field of Classification Search** D15/135,

D15/136, 138; 264/209.1; 425/380, 462,

425/467

See application file for complete search history.
